UNITED STATES PATENT OFFICE.

JAMES M. TEAHEN, OF DETROIT, MICHIGAN.

FLUSHING DEVICE FOR WATER-CLOSETS.

Application filed November 21, 1927. Serial No. 234,742.

The invention relates to flushing devices for water closets and has more particular application to that type of closet in which the velocity of movement of the water for flushing is developed through siphonic action. With such structures it is essential that the orifice through which the water from the tank is discharged into the bowl should be beneath the normal water seal so as to establish and to maintain siphonic connection with the tank until the seal is broken. On the other hand, it is necessary for the proper cleansing of the bowl that a certain amount of water should be introduced through the rim.

It is the object of the present invention to obtain a construction in which, during a portion of the time interval required for the flushing operation, an abundant quantity of water from the supply line is discharged through the rim into the bowl while during the remainder of the time all of the water from the supply is used for refilling the tank. This result is obtained through the operation of automatic mechanism as hereinafter set forth.

In the drawings;

Figure 1 is a vertical section through a portion of the bowl and the tank integral therewith showing my improved flushing device applied thereto.

Figure 2 is an enlarged view showing the automatic float controlled valve.

Figure 3 is a view similar to Figure 2 showing the valve in open position.

As shown in Figure 1 A is the water closet bowl which is formed integral with a tank B. C is a channel leading from the tank B to a discharge orifice D within the bowl which is located below the normal level of the water seal indicated by the line E. The passage C is normally closed by the float ball flush valve F which when raised from its seat operates in the usual manner to permit the free discharge of the contents of the tank.

The water supply connection for the tank is operated by a float controlled valve usually known as the ball cock which, upon the fall of the water level in the tank, is opened and is closed upon the refilling of the tank to the normal height. Inasmuch, however, as the water admitted through the ball cock is also used for the rim flush, I have devised a control mechanism of the following construction; G is the water supply conduit

which is shown as entering through the bottom of the tank B and rising to near the top thereof. H is a fitting at the upper end of said conduit containing the seat I for the valve J located in a cylindrical upward extension of the fitting and operated by the float lever K. The cylinder I communicates with the laterally extending conduit L which in turn communicates with a conduit M leading to the rim flush and a conduit N for discharging into the tank. These passages are so fashioned that the water from the passage L is directed downward toward the discharge conduit N and only when the latter passage is restricted will it pass into the conduit M leading to the rim flush.

As specifically shown the fitting H has an S-shaped portion extending from a passage L to the passage N with an annular enlargement N' surrounding and communicating with the passage N. O is a hollow piston valve slidably engaging the passage N and forming a downward extension thereof. P is a float at the lower end of the member O which is so located and of such buoyancy that when the tank B is filled to its normal level the piston O will be held in raised position between the annular passage N' and said passage N. This will compel a greater portion of the water entering through the passage L to discharge through the conduit M making a return-bend around a partition or deflector M'.

With the parts constructed as described, in operation whenever the flush valve F is raised the water in the tank H will first pass through the conduit C into the bowl raising the level in the latter to a point where it will establish siphonic action. This discharge from the tank will lower the level therein, the first effect of which is to open the ball cock J so that water from the supply conduit G is admitted into the fitting H. At this time the hollow piston valve O being in raised position, substantially all of the water entering the fitting H is compelled to pass through the conduit M to the rim of the bowl where it will discharge to wash the walls of the bowl. The action continues in this way until the water in the tank is almost completely discharged whereupon the falling of the water away from the float P will permit said float and the valve O to drop, opening connection through the hollow piston to the tank. The continued discharge of water from the ball cock will then be directed

- downward through the hollow piston O refilling the tank until nearly full whereupon the float P will raise the hollow piston to cut off further discharge.
- 5 The rise of the float and hollow piston valve is delayed by the pressure of the water against the upper end of said valve and also by the friction of the water flowing downward therethrough. Its resistance is sufficient to hold the float from movement until the tank is nearly full whereupon the diminished volume of water passing the nearly closed ball cock will be insufficient to balance the float and the latter will rise again 10 closing the passage N'. It is necessary, however, to still admit water to the tank so as to raise the level to a point for fully closing the ball cock as otherwise water would continue to flow through the passage N and rim.
- 15 A small quantity of water is required to pass this way so as to again establish the water seal in the bowl but further discharge would be only wasteful of water. I therefore preferably provide a restricted by-pass which, 20 when the valve O is fully closed, will still admit a small quantity of water into the tank. As shown this by-pass consists in one or more slots O' through the wall of the piston valve which register with the annular passage N' in the closed position of the valve O permitting the passage of sufficient water to complete the filling of the tank. The quantity so admitted is, however, small in comparison with the full quantity of water passing the ball cock when the latter is fully open so that the efficiency of the rim flush is not materially diminished. The elements of the structure just described may be formed in any suitable way but I prefer to form the 25 hollow piston valve O and the float P integral and of vulcanized rubber or an equivalent material. I also limit the movement of the valve O by a pin or set screw Q passing through the wall of the passage N and engaging a slot R in the member O. This will hold the parts from accidental disengagement but will permit of a normal functioning.
- 30 The construction of the mechanism above described is in effect a timing device which for a portion of the interval required for flushing, discharges substantially the full volume of water from the ball cock through the rim and in a succeeding interval directs 35 said discharge into the tank to refill the same. This timing is, however effected by means available, viz, the change of water levels within the tank in cooperation with the float controlled piston valve. Thus I 40 avoid complexity in construction and accomplish a perfect timing of the discharge which reduces the quantity of water required to the minimum.
- 35 What I claim as my invention is:
- 45 1. The combination with a water closet
- bowl and a flushing tank therefor, of a water supply connection for said tank, a ball cock controlling said water supply connection and means for directing the discharge from said ball cock alternately through the rim of the 50 bowl and into the tank for refilling the same.
2. The combination with a water closet bowl and a flushing tank therefor, of a water supply connection for said tank, a ball cock controlling said water supply connection, a conduit into which the water from said ball cock is discharged having branches respectively leading to the rim of the bowl and into the tank, and means operating during the 55 interval in which the water is discharging from the tank for directing the greater part of the water admitted to said conduit through the branch leading to the rim and for then directing the greater part of the water into the tank to refill the same.
3. The combination with a water closet bowl and a flushing tank therefor, of a water supply connection for said tank, a ball cock controlling said water supply connection, a conduit into which the water from said ball cock is discharged having branches leading 60 respectively to the rim and into the tank and means operated by the fall and rise of water in the tank for discharging the greater part of the water admitted to said conduit through the rim branch during the discharge of water from the tank for then directing the greater part of the water into the tank to refill the same and finally dividing the water to complete the filling of the tank and 65 re-establish the water seal in the bowl.
4. The combination with a water closet bowl and a flushing tank therefor, of a water supply connection, a ball cock controlling the discharge of water from said water supply connection, a conduit into which the water from said ball cock is discharged having a laterally extending branch leading to the rim of the bowl and a downwardly extending branch for discharging into the tank, a float operated valve controlling the latter branch normally substantially closed to direct the greater part of the water through the rim branch and opening when the tank is substantially emptied to admit water for 70 refilling the same and means for delaying the reclosing of said valve until the tank is nearly full.
5. The combination with a water closet bowl and a flushing tank therefor, of a water supply connection for said tank, a ball cock controlling said water supply connection, a conduit into which the water from said ball cock is discharged having branches leading 75 respectively to the rim of the bowl and downward into said tank, a hollow piston valve telescopically engaging said downward branch controlling the admission of water thereto, a float for holding said piston valve normally substantially closed to direct the 80

greater part of the water to the rim, said float being adapted to drop when the tank is nearly empty to open said valve and to permit the flow of water therethrough into the tank to refill the same, the resistance of said flow of water being adapted to delay the rising of said float until the tank is nearly full.

6. The combination with a water closet bowl, a flushing tank therefor, a water supply connection for said tank and a ball cock controlling said water supply connection, of means for alternately directing water to discharge through said ball cock to the rim of the bowl and into the tank comprising a conduit having laterally and downwardly extending branches, a hollow piston valve tele-

scopically engaging said downwardly extending branch, a float for normally holding said hollow piston valve in raised position where it intercepts communication to said downwardly extending branch, said float being adapted to drop when the tank is nearly empty to open communication with said downwardly extending branch and to permit flow of water therethrough for refilling the tank, said flow delaying the rising of said float and closing of said valve until the tank is nearly full and a restricted by-pass opened into said tank when said valve is closed to complete the refilling of the tank.

In testimony whereof I affix my signature.

JAMES M. TEAHEN.
